US00D684947S

(12) **United States Design Patent**
Motoishi et al.

(10) **Patent No.:** **US D684,947 S**
(45) **Date of Patent:** **** Jun. 25, 2013**

(54) **COMBINED AUDIO SYSTEM AND DIGITAL PHOTO FRAME**

D587,261 S 2/2009 Skaf et al.
D599,801 S 9/2009 Skaf et al.
D600,251 S 9/2009 Pondl

(75) Inventors: **Takuya Motoishi**, Tokyo (JP); **Kuninori Hyogo**, Tokyo (JP)

(Continued)

(73) Assignee: **Sony Corporation**, Tokyo (JP)

JP D1087098 S 10/2000
JP D1087812 S 10/2000

(**) Term: **14 Years**

(Continued)

(21) Appl. No.: **29/371,227**

(74) Attorney, Agent, or Firm — Rader, Fishman & Grauer PLLC

(22) Filed: **Dec. 6, 2010**

FIG. 1 is a perspective view of a first embodiment of a combined audio system and a digital photo frame showing our new design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

FIG. 7 is a perspective view of a second embodiment of a combined audio system and a digital photo frame showing our new design;

FIG. 8 is a front elevational view thereof;

FIG. 9 is a left side elevational view thereof;

FIG. 10 is a right side elevational view thereof;

FIG. 11 is a top plan view thereof; and,

FIG. 12 is a bottom plan view thereof.

The dot-dash broken lines represent the bounds of the claimed design while all other broken lines are included for the purpose of illustrating the unclaimed portions of the article; the broken lines form no part of the claimed design.

1 Claim, 8 Drawing Sheets
